FUR SCARF HANGER

Filed April 14, 1930

UNITED STATES PATENT OFFICE

JACOB M. HOLSTEIN, OF NEWARK, NEW JERSEY

FUR-SCARF HANGER

Application filed April 14, 1930. Serial No. 444,185.

This invention relates in general to a device for displaying fur scarfs and the like, and more particularly the invention is directed toward a hanger from which a scarf can be suspended for display purposes.

One object of the invention is to provide a device of this character embodying novel and improved features of construction whereby a fur scarf may be suspended with the head upward or with the head downward as may be desired.

Another object is to provide a fur scarf hanger having novel and improved means to removably receive the clasp or the like usually associated with the head of a fur scarf, the hanger including a part for suspending the device from a horizontal support, so as to support the scarf with the head uppermost.

Other objects are to provide such a device having a novel and improved construction for receiving the rear paws of a fur scarf whereby the scarf may be suspended head downward; to provide a fur scarf hanger which shall be simple and inexpensive in construction and easy to use, and to obtain other advantages and results as will be brought out by the following description.

Referring to the accompanying drawing in which corresponding and like parts are designated by the same reference characters throughout the several views:

Figure 1 is a front elevation of a fur scarf hanger embodying my invention showing the manner of suspending a fur scarf therefrom with the head uppermost.

Figure 2 is a similar view showing the manner of suspending a fur scarf with the head downward.

Figure 3 is an enlarged front elevation of the device.

Figure 4 is a transverse vertical sectional view on the line 4-4 of Figure 3.

Figure 5 is a horizontal sectional view on the line 5-5 of Figure 3, and

Figure 6 is a sectional view on the line 6-6 of Figure 3.

Specifically describing the illustrated embodiment of the invention the hanger includes a body 1 which may be formed of any suitable material, for example, leather, fibre or the

like, one end of the body having attached thereto a suitable suspending device such as a hook 2 by which the body may be suspended from a horizontal support such as a rail.

At the end of the body opposite the hook, and on the opposite edges of the body, inwardly directed slots 3 are provided, each of said slots including a constricted mouth or throat portion 4 which is narrower than the width of the leg portion of a fur scarf, 55 said throat portion leading into an enlarged end portion 5 which is of sufficient size to 60 freely receive the leg portion of a fur scarf, but is smaller than the paw portion. The slots 3 are spaced apart a distance substantially equal to the normal spacing of the paw portions of a fur scarf. In using the 65 device for hanging a scarf head downward, a rear leg portion A of a scarf B, indicated by dot and dash lines in Figure 2 of the drawings, is drawn inwardly through each slot 3 with the paw portion C disposed at the rear side of the body 1. The enlarged paw portion cannot be pulled through the enlarged end 5 of the slot, so that when the 70 hanger is suspended by the hook 2 from a rail or the like, the fur scarf hangs downwardly from the body 1 with the head portion lowermost. The constricted portions 4 of the slots prevent the leg portions A from 75 becoming accidentally detached during handling of the hanger with a scarf attached.

Obviously the fore paws of the scarf might be arranged in the slots 3 in the same manner to support the scarf with the head 80 uppermost, if desired.

For supporting a fur scarf with the head portion uppermost, the body 1 is provided with a pair of parallel slots 6 in which are 85 slideable a pair of loops 7, said slots being vertically exposed when the body 1 is suspended by the hook 2. These loops 7 are adapted to receive between them and the body 1, one jaw piece 8 of the clasp D or the like usually associated with the head 90 portion of a fur scarf to simulate the jaws and to connect the head end of the scarf to the tail or body portion. The loops 7 are adjustable relatively to each other in 95 the slots 6 to accommodate clasps of differ- 100

ent sizes, this adjustability of the loops being generally illustrated by dot and dash lines in Figures 3 and 4 of the drawings. In inserting the jaw-piece 8 of a clasp in the loops, preferably the operating end 9 of the jaw is first slipped through the loop 7 which is lowermost when the hanger is suspended, after which the other loop 7 is adjusted in the slots and slipped over the clamping end 10 of the jaw-piece 8. This results in the attachment of a fur scarf, for example, as indicated by dot and dash line E in Figure 1 of the drawing, so that when the hanger is suspended from a horizontal support, the scarf hangs downwardly with the head portion uppermost.

Where the body 1 is made of flexible material such as leather, it is necessary to reinforce the lower portion of the body to support the paws, and for this purpose I may secure to the rear side of the body, as by rivets 12, a strip 13 of metal or the like.

Obviously the details of construction of the device may be widely modified and changed by those skilled in the art without departing from the spirit or scope of the invention; furthermore, a plurality of pairs of slots 6 and 3 may be provided in a single body so that a plurality of scarfs can be suspended from the same hanger. Therefore I do not desire to be understood as limiting myself in the construction of the device except as required by the following claim when construed in the light of the prior art.

Having thus described my invention, what I claim is:

A fur scarf hanger comprising a body formed with a pair of parallel slots and having suspending means at one end, and a pair of loops slideable in said slots to receive and hold a clasp of a fur scarf between them and said body, said loops being adjustable to accommodate clasps of different sizes.

JACOB M. HOLSTEIN.
